DESIGN FOR A RECORDER CASING OR THE LIKE

George H. Kress, Vestal, N. Y., and Carl W. Sundberg, Detroit, Mich., assignors to International Business Machines Corporation, New York, N. Y., a corporation of New York

Application December 19, 1946, Serial No. 135,624

Term of patent 14 years

(Cl. D26—14)

To all whom it may concern:

Be it known that we, George H. Kress and Carl W. Sundberg, both citizens of the United States, residing, respectively, in Vestal, county of Broome, and State of New York, and in Detroit, county of Wayne, and State of Michigan, have invented a new, original, and ornamental Design for a Recorder Casing or the like, of which the following is a specification, reference being had to the accompanying drawing, forming part thereof.

Fig. 1 is a perspective view of a recorder casing showing our new design;

Fig. 2 is a front elevation thereof; and
Fig. 3 is a top plan view thereof.

We claim:

The ornamental design for a recorder casing or the like, substantially as shown.

GEORGE H. KRESS.
CARL W. SUNDBERG.
